PROTECTIVE EYE SHIELD

Mildred K. Holly, Maynard, and Abraham L. Lastnik,
Framingham, Mass., assignors to the United States of America as represented by the Secretary of the Army

Filed Jan. 21, 1963, Ser. No. 73,266

Term of patent 14 years

(Cl. D57—1)

(Granted under Title 35, U.S. Code (1952), sec. 266)

FIG. 2

The side not shown is substantially like the side shown.

The invention described herein, if patented, may be manufactured and used by or for the Government for governmental purposes, without the payment to us of any royalty thereon.

We claim:

The ornamental design for a protective eye shield, substantially as shown and described.
